UNITED STATES PATENT OFFICE.

ROBERT E. LEE, OF MARIETTA, OHIO.

LIQUID-SOAP DISPENSER.

1,325,567.

Specification of Letters Patent.

Patented Dec. 23, 1919.

Application filed March 26, 1919. Serial No. 285,293.

To all whom it may concern:

Be it known that I, ROBERT E. LEE, a citizen of the United States, residing at Marietta, in the county of Washington and State of Ohio, have invented a new and useful Liquid-Soap Dispenser, of which the following is a specification.

This invention relates to a device for dispensing liquid soap, one of its objects being to provide a simple and compact structure having novel means for ejecting a jet of liquid soap downwardly onto the hands of the user the said apparatus, at each operation, discharging a measured quantity 15 of the soaps.

Another object is to provide a structure of this character which can be taken apart easily to facilitate cleaning and to allow for the replacing of broken parts, etc.

With the above and other objects in view, which will appear as the description proceeds, the invention resides in the combination and arrangement of parts and in the details of construction hereinafter described 25 and claimed, it being understood that, within the scope of what is claimed, changes in the precise embodiment of the invention shown can be made without departing from the spirit of the invention.

In the accompanying drawings the preferred form of the invention has been shown.

In said drawings:

Figure 1 is a plan view of the device.

Fig. 2 is a central vertical section there- 35 through on line 2—2 Fig. 1.

Fig. 3 is a section through the bottom of a slightly modified form of structure.

Referring to the figures by characters of reference 1 designates an attaching bracket 40 provided with a ring 2 integral therewith: This ring is interiorly screw threaded and is adapted to engage the threaded neck portion 3 of a container 4 and thus suspend the said container. The container may be made 45 of glass suitably ornamented and can be provided with a flat bottom as shown in Fig. 1 or, if preferred, can be formed with an outlet opening 5 in the bottom thereof surrounded by a depending threaded flange 50 6 for engagement by a cap 7 constituting a bottom closure.

A cap 8 is adapted to engage the upper portion of the threaded neck 3 and to serve as a lock nut to prevent the ring 2 from un- 55 screwing. This cap carries a central guide

tube 9 the lower end of which is preferably enlarged as shown. An opening 10 is formed in the cap in line with the center of the tube and depending from the cap and concentric at its upper end with the opening 60 10 is another tube 11 the lower end of which opens into a casting or cap 12 forming a measuring chamber and having a radially extending portion 13. An outlet 14 is formed in the top of this portion 13 and has 65 a delivery tube 15 extending upwardly therefrom and through the cap 8, the outwardly projecting portion of the tube being curved and terminating in a downwardly extending nozzle 16.

One or more openings 17 are formed in the wall of the tube 11 and normally supported above these openings and within the tube is a piston 18 connected to the lower end of a rod 19. Said rod extends through the guide 70 tube 9, the upper end of the rod being screw threaded as shown at 20 for engagement with a sleeve 21 slidably mounted in the tube 9 and having a knob 22 at its upper end. A coiled spring 23 is mounted in the tube 9 80 between the sleeve 21 and the cap 8 and serves to hold the sleeve normally elevated and the piston 18 normally positioned above the opening or openings 17.

In using the device the liquid soap is 85 placed in the container 4 after first unscrewing the cap 8 from the neck 3 and lifting the tubes 11 and 15 from the container. The cap is then replaced so that the two tubes will extend downwardly into the bottom 90 portion of the container and a portion of the liquid will flow through the opening 17 and fill the chamber 12. By pressing downwardly on the knob 22 the piston 18 will be forced downwardly, promptly closing the 95 opening 17 and forcing from the chamber 12 any liquid contained therein, this liquid passing upwardly through the tube 15 to the nozzle 16 where it rebounds from the wall of the nozzle and is directed downwardly 100 onto the hands of the user.

It will be noted that the different parts can be separated readily for the purpose of cleaning and repairing them.

What is claimed is:

1. In a device of the class described the combination with an attaching bracket, and a ring outstanding therefrom, and having threads therein, of a container having a threaded neck extending through the ring 110

and engaging the threads therein, and a cap engaging said threaded neck and binding upon the ring to constitute a lock nut.

2. In a soap dispenser the combination
5 with a container, and a cap removably mounted thereon and constituting a closure therefor, of a guide tube extending upwardly from the cap, a tube depending from the cap and having an outlet opening at its
10 lower end and an inlet opening adjacent said end, a cap mounted on the lower end of said depending tube and having an outlet extension projecting from the outlet opening, a piston mounted to reciprocate within
15 the depending tube, a rod extending therefrom and into the guide tube, a knob adjustably engaging the rod and slideable within the guide tube, a spring housed within

the guide tube and bearing against the knob and the cap for holding the piston normally 20 elevated above the inlet opening in the depending tube, an outlet tube extending from the outlet extension on the depending tube and through the cap, and a nozzle at the outer end of said tube and extended at an 25 abrupt angle therefrom, the cap on the lower end of the depending tube being mounted on the bottom of the container.

In testimony that I claim the foregoing as my own I have hereto affixed my signature in the presence of two witnesses.

ROBERT E. LEE.
